UNITED STATES PATENT OFFICE.

IRVING HEIDELSHEIMER, OF NEW YORK, N. Y.

DESIGN FOR A SHANK FOR CUFF-LINKS.

49,887.

Specification for Design.

Patented Nov. 14, 1916.

Application filed June 16, 1916. Serial No. 104,125. Term of patent 3½ years.

To all whom it may concern:

Be it known that I, IRVING HEIDELSHEIMER, a citizen of the United States, residing at the borough of Manhattan, city, county, and State of New York, have invented a new, original, and ornamental Design for a Shank for Cuff-Links, of which the following is a specification, reference being had to the accompanying drawing, forming a part thereof.

Figure 1 is a side elevation of the shank showing my new design, with the buttons or

faces attached, and Fig. 2 is a similar top plan view.

I claim:

The ornamental design for a shank for cuff links, as shown.

In testimony whereof I have signed this specification in the presence of two subscribing witnesses.

IRVING HEIDELSHEIMER.

Witnesses:

M. M. RIEMANN,
A. C. PARHAM.
